DESIGN FOR A COMBINED CANDELABRUM
AND FLOWER VASE

Agnes E. Thienhaus, Milwaukee, Wis.

Application November 23, 1946, Serial No. 135,032

Term of patent 7 years

(CL. D48—2)

To all whom it may concern:

Be it known that I, Agnes E. Thienhaus, a citizen of the United States and resident of Milwaukee, in the county of Milwaukee and State of Wisconsin, have invented a new, original, and ornamental Design for a Combined Candelabrum and Flower Vase, of which the following is a specification, reference being had to the accompanying drawing, forming part thereof.

Figure 1 represents a front elevation of my combined candelabrum and flower vase, showing my new design.

Figure 2 is a rear view of the same.

Figure 3 is a side elevation.

Figure 4 is another side elevation looking in the opposite direction.

Figure 5 is a plan view of the same.

I claim:

The ornamental design for a combined candelabrum and flower vase, as shown.

AGNES E. THIENHAUS.
